UNITED STATES PATENT OFFICE.

WILLIAM L. LARGE, OF NEW YORK, N. Y.

HEADLIGHT-SHUTTER.

1,204,888.

Specification of Letters Patent. Patented Nov. 14, 1916.

Application filed June 21, 1916. Serial No. 104,946.

To all whom it may concern:

Be it known that I, WILLIAM L. LARGE, a citizen of the United States, and a resident of the city of New York, borough of Brooklyn, in the county of Kings and State of New York, have invented a new and Improved Headlight-Shutter, of which the following is a full, clear, and exact description.

This invention relates to headlights for 10 automobiles or other vehicles and has particular reference to means for varying the density of the light being projected therefrom.

Among the objects of the invention is to 15 provide a headlight of novel construction or an attachment for existing lamps in which there are provided a plurality of shutter elements so arranged and manipulated as to obstruct more or less of the light according 20 to requirements, the means to manipulate the same being controlled by electric means within reach of the driver or other person.

Another object of the invention is to provide controlling means for adjustable headlight shutters comprising a small electromagnet and means whereby repeated impulses given to the armature through the magnet will operate the shutter elements to close and open the same step by step.

With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same parts 40 in the several views, and in which—

Figure 1 is a front elevation of the shutter devices, the frame being in section on the line 1—1 of Fig. 2; Fig. 2 is a vertical section on the line 2—2 of Fig. 1; Fig. 3 is a front elevation of actuating and controlling means for the shutters, parts being in section on the line 3—3 of Fig. 4; Fig. 4 is a horizontal section on the line 4—4 of Fig. 3; Fig. 5 is a vertical section on the line 5—5 of Fig. 1; Fig. 6 is a vertical sectional detail on the line 6—6 of Fig. 1; Fig. 7 is an end elevation of the actuating means for the shutters as viewed from the line 7—7 of Fig. 1, full lines showing the shutter devices in 55 closed position and dotted lines showing the same in half open position; Fig. 8 is a view similar to Fig. 7 but showing the full open position of the shutter devices; Fig. 9 is a sectional detail on the line 9—9 of Fig. 3; and Fig. 10 is a vertical detail as seen from the line 10—10 of Fig. 4, looking forwardly.

Referring now more particularly to the drawings, I show a frame 12 to which is secured a casing 13 having a lens or window 14 carried thereby. The frame and casing 65 parts indicated may represent either an attachment to an ordinary lamp casing indicated at C or any new construction. They may represent a complete lamp casing, the design or mechanical construction of these 70 casing parts being adapted for modification according to individual desires or the equipment to which the improvement is to be fitted.

Secured within the casing 13 as upon the outer face of the frame member 12, I provide a pair of brackets 15 and 16, shown in this instance as being arranged vertically and parallel to each other on opposite sides of the side opening 17 of the device. A series of shutter elements 18 are journaled for oscillation around parallel axes in the forwardly projecting flanges of the brackets 15 and 16. Each shutter element has connected to its ends a pair of clips 19 and 20 which project rearwardly on the sides of the pivot flanges of the brackets 15 and 16, and from each of the clips there projects inwardly a pivot stud 21. By this means the ends of each shutter element operate close to the 85 sides of the forwardly projecting flanges of the main brackets. Said flanges, however, are notched at 22 to provide for the swinging of the clips upwardly and rearwardly around the axes of the studs 21, see Figs. 5, 95 7, and 8. From these figures it will be observed that the axis of each shutter element lies below the longitudinal center of such element when it is in its closed position and comparatively close to the rear face thereof. 100 Also each shutter element is adapted for swinging movement through approximately ninety degrees from its closed position to its full open position, compare Figs. 7 and 8. I also provide for an adjustment of the shutter elements at an intermediate position, see dotted lines Fig. 7.

As shown in Fig. 1, when the shutter elements are closed a comparatively small amount of light will be projected from the 110

lamp through the small space left below the lowermost shutter element. When the shutter elements are half open, as indicated in Fig. 7 in dotted lines, the light will be projected forwardly and downwardly upon the roadway and practically all of the glare will be prevented, but as indicated in Fig. 8, when the elements are wide open, there will be practically no obstruction to the light, the shutter elements being of negligible thickness so far as the obstruction of the light is concerned. A bar 23 extends along one end of the series of shutter elements and is pivotally-connected to all of them through studs 24 projecting outwardly from the clips 19. This bar serves, therefore, to so connect the several shutter elements that they will always be held in parallel planes. Guide means 25 is applied to the bracket 15 to confine the bar 23 in any suitable fixed plane, herein shown as vertical, permitting it, however, to be moved in such plane for actuating the shutter elements.

At any convenient place, as in the lower portion of the casing 13, I provide a bracket 26, in or to which the principal actuating and controlling devices are secured. A pinion 27 is connected to a shaft 28 that is journaled in a pair of forwardly projecting vertical parallel flanges of said bracket. On the outside of the bracket a crank wheel 29 is secured to said shaft, the same carrying a wrist pin 30 having thereon an anti-friction roller co-operating with the lower end of the bar 23 in a horizontal slot 32. The body of the roller 31 approximately fills the space between the upper and lower edges of the slot, whereby there is practically no lost motion. The pinion 27 and shaft 28 are designed to be given a step by step rotation in a constant direction and thereby the bar 23 is actuated into and held in three different positions, as indicated, corresponding to the open, closed, and mid positions of the shutter elements. Said positions of the bar are determined, therefore, by the relative positions of the fixed pivots 21 and the bar pivots 24. Any suitable means may be provided to operate the pinion and shaft and positively hold the same from movement when desired. The means provided herein serve to cause the rotation of the pinion and shaft in four successive steps, ninety degrees of movement being provided for each step, as seen in Figs. 7 and 8. With the wrist pin and roller revolving around the axis of the shaft 28 in the direction of the arrows, the bar 23 will be given vertical reciprocation. In Fig. 60 7, the bar is at its uppermost position and likewise the pivot pins 24 are at their highest position and the shutter elements are closed. At the next step of rotation of the shaft 28, the bar will be lowered to the position shown in dotted lines in Fig. 7

and the shutter elements will be half-open, and then at the next quarter revolution of the roller 31, the bar 23 will be at its lowermost position with the shutter elements wide open. At the next quarter turn, the roller gliding toward the front end of the slot 32 and moving upwardly will lift the bar again, so that it will occupy the position shown in dotted lines in Fig. 7, with the shutter elements again half-way open. It will be understood, therefore, that with the wheel 29 rotated in a single direction step by step, the roller will be driven to and fro along the slot 32 and the bar 23 will be reciprocated up and down with such forward and rearward movement as will be incidental to the swinging of the pivots 24 around their respective centers 21.

I will now describe the means I provide for actuating the pinion 27 and parts connected thereto. In one end of the bracket 26 or any other suitable fixed support, is an electromagnet 33 having an armature 34 pivoted at 35 along its front edge in a bracket extension 26'. By means of a push button 36 and battery 37 or other suitable source of energy, the electromagnet may be energized for the purpose of swinging the armature upwardly around its pivot, the armature dropping again by gravity when the magnet is deenergized in a well known manner. A blade 38 is connected to the armature and projects rearwardly beneath a plunger 39 mounted for vertical movement in guides 40 fixed to the bracket 26.

At 41 I show a master gear mounted on a shaft 42 below and parallel to the pinion shaft 28 and journaled similarly in the bracket 26. This master gear is in the nature of a combined spur gear and lantern pinion having teeth 43 meshing with the teeth of the pinion 27 and indicated as having twice the number. This member also has a series of bars 44 indicated as eight in number and arranged circumferentially around and parallel to the shaft 42. To give a quarter rotation to the pinion 27, therefore, it is necessary to actuate the master gear through one-eighth of a rotation or through the space of one bar 44. 45 indicates a lock having a point projecting normally between two adjacent bars 44, see Fig. 5. This lock comprises a plate pivoted at 46 upon a portion of the bracket 26, and a tension spring 47 serves to hold the point of the lock in its locking position as indicated above. One end of the spring is secured to a fixed point at 48 on the bracket adjacent the electromagnet, and the other end of the spring is connected to a pin 49 projecting through a short arc-shaped slot 50 formed in the upper portion of the lock plate. Said pin 49 is connected to a pawl 51 pivoted at 52 upon the lock plate. The slot 50, like another slot 53, is concentric with the pivot 52, 125

and the pawl 51 carries another pin 54 which projects at one end into or through the slot 53 and at its other end rearwardly for cooperation with the cam-shaped end of a lever 55 pivoted at 56 on the frame 12 beyond the electromagnet. The lever 55 is connected by a horizontal pin 57 with the magnet operated plunger 39. As shown in Figs. 1 and 10, the cam end of the lever 55 lies below the pin 54, while the spring 47 serves to hold the lock in locking position and also the pin 54 against the end of the lever and substantially between the lever and the pivot 52. When, therefore, an impulse is given to the electromagnet and the plunger 39 is lifted, the cam end of the lever 55 wiping against the pin 54, will throw the upper portion of the lock plate in a direction away from the lever and thereby the point of the lock will be withdrawn from its normal holding position. When the magnet is deenergized, the lever 55 will drop to normal position under the force of gravity and a tension spring 58 anchored at its lower end at 59. During this movement, the cam end of the lever wipes downwardly past the pin 54, the pins 54 and 49 at this time moving along the slots 53 and 50 respectively against the force of the spring 47 which immediately thereafter carries the pin 54 back to its normal position.

The pin 57 carried by the plunger 39 is connected to another lever 60 pivoted on a fixed pivot 61. This is a lever of the first class, while the lever 55 is of the third class. The other end of the lever 60 is connected by a pin 62 to another lever 63 pivoted at 64. The remote end of this lever 63 is forked and cooperates with a pin 65 secured to a vertical slideable shoe 66 having a pivoted tooth 67 pivoted at 68 and cooperating with a leaf spring 69, see Fig. 5. The shoe 66 is in the nature of a rack having a single tooth, said tooth lying normally directly below the next bar 44 to be engaged. At the same time the plunger 39 moves upwardly to withdraw the lock, the levers 60 and 63 will be actuated around their respective pivots and the shoe 66 and its tooth 67 will be elevated far enough to move the bar 44 engaged thereby to the next position or through one-eighth of a rotation of the master gear 41. In other words, as the lock moves downwardly from engagement with the bars 44, the tooth 67 begins to move upwardly, causing the partial rotation of the master gear. As soon as this movement is imparted to the master gear, the lock snaps back into locking position and when the shoe 66 is brought back to its normal position by the combined force of gravity and the spring 58, the point of the tooth 67 will glide idly over the next bar to be engaged.

From the foregoing specific description

of the mechanism illustrated, the operation of the device may be briefly summarized as follows: At each impulse given to the electromagnet by closing the circuit therethrough, the master gear will be rotated through one-eighth of a turn and will be locked at the end of such partial rotation by the point of the lock 45, the spring 47 acting to throw the lock in such position irrespective of the position of the magnet operated levers. The shutters, for example, being closed and it is desired to project a moderate amount of light forwardly and downwardly upon the roadway, a single impulse given to the magnet will effect this result, and if the shutter elements are to be drawn wide open, another impulse given in the same manner will cause the same. In other words, to adjust the shutter elements to any desired position from whatever position they may happen to occupy at any time, all that is required is for one or a few quick movements of the operator's finger to be given to the button or switch 36 and the desired result will be accomplished. The operating parts occupy a very slight amount of space within the casing 13, and hence are either invisible or inconspicuous. The operation is simple, easy, and positive and the desired control of the intensity of the light is enjoyed.

I claim:

1. The herein described headlight comprising a plurality of shutter elements mounted for oscillation around parallel axes, a bar pivotally connecting all of said elements and serving to hold them in parallel planes, rotary means connected to said bar to impart to it positively reciprocating movements in opposite directions, and means to actuate said rotary means intermittently step by step always in the same direction.

2. In a dimmer for headlights, the combination of a pivoted shutter element, a bar connected to the shutter element eccentrically of its pivot, a rotary member having pin and slot connection with the bar, and means to rotate the rotary element in a continual step by step manner in the same direction to reciprocate the bar in opposite directions and cause to and fro oscillation of the shutter elements, each oscillation comprising a plurality of steps in the same direction.

3. In a headlight dimmer, the combination of a frame, a pair of brackets secured to opposite sides of the frame, a series of shutter elements having pivotal connection with said brackets, a bar connecting all of said elements and serving to hold them in parallel planes in either open, closed or intermediate positions, a rotary member connected to said bar, means to give the rotary element a step by step continual movement of rotation in the same direction for changing the position of the shutter elements from one step to another in either direction, and

locking means serving automatically to hold the bar and shutter elements positively after each movement thereof.

4. In a headlight shutter, the combination 5 with a series of shutter elements mounted for oscillation around parallel axes and a rigid bar connected to all of said elements to control their position, said bar having a slot perpendicular to the line of pivot connections with said elements, of a rotary member having a crank connection in said slot with the bar, and means to rotate the rotary member continually step by step in the same direction whereby the crank connection with the bar will positively cause the bar to reciprocate in opposite directions to both open and close the shutter elements.

5. The combination with a series of shutter elements mounted to oscillate around 20 parallel axes and a rigid bar having similar pivotal connection with all of said elements, said bar having a slot perpendicular to the line of pivotal connections, of means to positively reciprocate the bar in opposite directions and oscillate the shutter elements comprising a rotary member having a crank connection with said slot, each of said oscillations comprising a plurality of steps, electromagnet means to actuate the rotary member step by step in a continual direction, and an automatic lock coöperating with

the rotary member to hold it in fixed position after each step of its movement.

6. The combination with an oscillating shutter element, of actuating and controlling means for said element comprising a rotary member, a wrist pin connected to the rotary member, a reciprocating link connection between the wrist pin and the shutter element, said link having a slot for said wrist pin perpendicular to the direction of reciprocation of the link, an electromagnet having a movable armature, and devices adapted to be actuated step by step by repeated impulses given to the magnet to cause the rotary member to be rotated step by step in a continual direction.

7. The combination with an oscillating pivoted shutter element, a link connected thereto and means to actuate said link to oscillate the shutter element to and fro around its axis, of means to control said actuating means including an electromagnet having a movable armature, a plurality of levers operated directly from said armature, connections between one of said levers and the actuating member to operate it and the shutter, and means actuated by the other of said levers to positively lock the actuating means and shutter element from movement after being actuated.

WILLIAM L. LARGE.
